UNITED STATES PATENT OFFICE.

WILLIAM HENRY LAREW, OF MARIPOSA, CALIFORNIA.

ADJUSTABLE MAP OR CHART SUPPORT.

SPECIFICATION forming part of Letters Patent No. 392,565, dated November 6, 1888.

Application filed July 24, 1888. Serial No. 280,932. (No model.)

To all whom it may concern:

Be it known that I, WILLIAM HENRY LAREW, of Mariposa, Mariposa county, State of California, have invented an Improvement in 5 Adjustable Map or Chart Supports; and I hereby declare the following to be a full, clear, and exact description of the same.

My invention relates to an apparatus for use in schools and for similar purposes; and it 10 consists of a frame and adjustable sliding boards guided so as to travel up and down upon the standards of the frame and connected together so as to be moved simultaneously.

It also consists of clamps and holders for 15 charts and papers, and in certain details of construction, all of which will be more fully explained by reference to the accompanying drawings, in which —

Figure 1 is a perspective view of my apparatus. Fig. 2 shows one end of the bar in a 20 plan view and the other in vertical longitudinal section. Fig. 3 is a vertical cross-section of the same.

My present invention is an improvement 25 upon a similar device, for which patent was issued to me May 29, 1888.

A A are standards, which are preferably made cylindrical in form, and they have upon 30 their upper ends the sleeves or ferrules B. From each of these sleeves plates C project toward each other when the standards are in the proper position, and they overlap, as shown. Holes are made through these plates, and screws D pass through the holes into the ends 35 of the horizontal top bar, E, which has also sleeves or ferrules F upon its ends. The upper ends of the legs are thus united to the cross-bar by a strong and ornamental joint.

The standards A diverge from each other 40 toward the bottom, near which each pair is united by a cross-bar, G, the ends of which fit into the T-shaped ferrules H, which ferrules are fitted and secured upon the uprights or standards A.

Upon the bottoms of the uprights A are fitted 45 casters I, the sockets of the casters fitting over the ends of the legs and holding them firmly, preventing them from splitting, and at the same time forming an ornamental finish to the 50 legs.

J J are links, which have one end pivoted to the T-shaped ferrules H. These links ex-

tend toward each other, and are slotted, as shown, so that the screw-pin K passes through the slots, and by means of thumb-nuts L the 55 links may be fixed together at any desired point of overlap. By this construction it is manifest that the uprights A may be separated or closed together by their hinges at the upper ends, and when adjusted to the proper point 60 of separation may be locked at this point by means of the thumb-nuts K, as above shown.

M M are boards having the guide-rings N fixed upon each corner. These boards are of such a length as to just fit between the pairs of 65 uprights A, and the guide-rings travel loosely upon the uprights. One of these boards is fitted to the front and the other to the rear pair of uprights, and the two are united together by the cords O, attached to their upper 70 edges and passing through pulleys P, which are secured to the ferrules at each end of the upper cross-bar. By this construction the two boards counterbalance each other, and they may be moved up or down upon the uprights A, so as to adjust the one which is temporarily in use to any desired height with relation to the eye of the pupil or observer. When one board is raised, it is manifest that the other will be correspondingly depressed, 75 80 and they will serve as counter-balances for each other. In connection with these boards I employ chalk or crayon holding cups Q, which are fitted by means of swivel-sleeves R to the guide-rings at the lower edges of the 85 boards, and these cups may be turned to the inside between the uprights, entirely out of the way, or they may be swung around to one side or to the front, so as to be convenient for use. These boards may be used simply as 90 blackboards, to be written or marked upon, or they may serve the important purpose of supporting paper or prepared cloth, upon which it may be desired to draw permanent diagrams or figures, and they also serve to support charts 95 or maps for other instruction.

In order to conveniently attach charts or maps, which are double or consist of many leaves, I employ cylindrical bars R", having slots cut entirely through them and extending 100 nearly from end to end. Grooves or channels S are made in the ends of these bars, corresponding to and forming continuations of the open slots. Rods T are bent at each end, as

shown in Fig. 2, so as to lie within these slots and hook over the ends of the bars. The rods extend along within one side of the slot and serve to separate the bight of the map or paper, which thus hangs from the rod, passing down through the slot and being supported upon the board M, above described. The ends of the rods are slipped into the loops or rings U at the tops of the boards, to which the counterbalanced cords O are connected, and may easily be slipped out and removed or replaced by others at any time.

When single sheets are to be supported upon the apparatus, I employ the elastic clamps V, which are curved into a scroll formed as shown, the bight or open central portion slipping over the upper edges of the boards, while the ends press upon the boards with sufficient elastic pressure to hold any sheet which it may be desired to attach temporarily to the boards. By this construction I am enabled to instantly attach any map, paper, chart, or prepared cloth upon which work is to be done or from which instructions are to be given. The boards themselves may be used to write or draw upon. These boards may be instantly raised or lowered, to suit any light that may fall upon them, and also to arrange them for any desired height or angle relative to the eye.

When it is desired to attach maps or charts of various sizes, which may have rings or permanent attachments, I employ the hooks W, which can be either placed upon the top bar of the frame for the larger maps or over the upper edges of the movable boards.

The whole device can be folded closely together at any time for transportation or to set it aside out of the way. It is light, portable, and strong.

Having thus described my invention, what I claim as new, and desire to secure by Letters Patent, is—

1. The cylindrical uprights A, having the sleeves or ferrules on their upper ends, and the overlapping perforated plates extending from said ferrules and through which screws or pins pass, in combination with the horizontal top rod or bar to which these uprights are hinged in pairs, and the slotted connecting-links J on the outer ends of the cross-bars G, with the screws and thumb-nuts, substantially as herein described.

2. The uprights A, connected together in pairs, and having their upper ends hinged to

a transverse connecting-bar, as shown, in combination with the boards M, having guides N traveling upon the uprights, the loops or attachments U upon their upper edges, and the connecting-cords passing over pulleys upon the top rail, substantially as and for the purpose herein described. 60

3. A map or chart support, consisting of two pairs of uprights mounted upon casters having the horizontal uniting-bars with their T-shaped ferrules and the adjusting-links and set-screws near the bottom, the ferrules and hinged joints at their upper ends, by which they are pivoted to the horizontal top bar, the boards M, having guides N upon their corners, which travel loosely upon the uprights, and the connecting-cords passing through pulleys at the top of the frame and uniting the boards so that they may be moved up or down simultaneously and counterbalance each other, substantially as herein described. 75

4. The slotted bars R, having grooves or channels at their ends corresponding and in line with the open slots, in combination with the rods T, extending centrally through one side of the slots and having their ends bent so as to fit into the grooves or channels at the ends of the bars, substantially as herein described. 80

5. The bars having open slots extending from end to end, the grooves or channels at the ends, and the bent or hook-shaped rods fitting these grooves or channels, in combination with the adjustably-sliding boards having the rings or loops U at their upper ends for the reception of the bars and to support the charts attached thereto, substantially as herein described. 85

6. The hinged adjustable uprights having the sliding boards guided so as to move up or down upon them, and connected together so as to counterbalance each other, and provided with loops or rings U at their upper ends, 90 in combination with the slotted grooved bars R, the rods T, upon which folded sheets are supported, said rods being bent so as to fit into the grooves or channels at the ends of the bars, substantially as herein described. 95

In witness whereof I have hereunto set my hand.

WILLIAM HENRY LAREW.

D. J. FOLEY.

Corrections in Letters Patent No. 392,565.

It is hereby certified that Letters Patent No. 392,565, granted November 6, 1888, for an improvement in "Adjustable Map or Chart Supports," was erroneously issued to the inventor, William Henry Larew, as sole owner of said invention; whereas the patent should have been granted to the said *William Henry Larew and W. C. Reid, of Mariposa Co., California, jointly*, said Reid being the owner of one-half interest, as shown by the assignments of record in the Patent Office; that the proper correction has been made in the files and records pertaining to the case in the Patent Office, and should be read in the said Letters Patent that the same may conform thereto.

Signed, countersigned, and sealed this 25th day of December, A. D. 1888.
